UNITED STATES PATENT OFFICE.

JAMES BENJAMIN ALLEN, OF DETROIT, MICHIGAN.

CASTING-BOX FOR LINOTYPE-MACHINES.

NO. 823,660.

Specification of Letters Patent.

Patented June 19, 1906.

Application filed August 18, 1903. Serial No. 169,874.

To all whom it may concern:

Be it known that I, JAMES BENJAMIN ALLEN, a citizen of the United States of America, residing at the city of Detroit, in the State of Michigan, have invented certain new and useful Improvements in Casting-Boxes in Linotype-Machines; and I do hereby declare the following to be a full, clear, and exact description of my said invention, such as will enable others skilled in the art to which it pertains to make and use the same.

The invention relates to machines of that character in which both the mold and the nozzle for the molten metal are reciprocated in relation to the alined matrices. Heretofore machines of that class have been made in which the reciprocatory mold is first moved against the matrices, following which the nozzle is engaged with the mold. It has been customary, however, to form the nozzle of conical shape and to provide a correspondingly-shaped cavity in the center of the mold to receive the nozzle, the jet-opening thereof being directed at different angles into the mold-cavity. As a consequence the molten metal is obliged to travel a greater distance within the mold-cavity to reach the matrices at opposite ends of the line than its travel in the center. This often results in forming a poor casting on account of the metal becoming chilled before reaching the end matrices.

It is the object of the present invention to obtain a construction in which the molten metal is introduced into the mold-cavity from a nozzle extending the full width thereof and, further, to form a flat bearing for the nozzle upon the mold, thereby insuring a perfect joint.

With these objects in view the invention consists in the peculiar construction, arrangement, and combination of parts hereinafter set forth.

In the drawings, Figure 1 is a perspective view of the mold, showing the same in position where the sections thereof are separated for the extraction of the cast slug. Fig. 2 is a vertical longitudinal section through a portion of the mold, showing it in adjacency to the matrices and the nozzle. Fig. 3 is a horizontal section of Fig. 2. Fig. 4 is a vertical section at right angles through the mold to Fig. 2 and partly in elevation. Fig. 5 is a view of a linotype-machine with my invention applied thereto.

A represents the matrices, to be selected and alined by mechanism not shown.

B is the mold in which the slugs are cast, and C is the nozzle through which molten metal is introduced into the mold.

As the present invention relates solely to the construction of the mold and the nozzle and their relation to the matrices, all other parts of the machine are omitted from the description, though they are shown in Fig. 5.

The mold B is formed in two sections *a* and *b*, both of which are sleeved upon a shaft D, and the section *b* being pinned to the shaft, so as to move therewith. The section *a* is at certain times locked to the section *b* by means of the spring-bolt E, having operating-lug F. This bolt E lies in a recess E', formed in portion *b*, and the lug F, secured to said bolt, works in a slot F'. A spring E'' serves to press the bolt outwardly into a slot *a'*, formed in the portion *a*, thus locking the portions together. When in locked position, the sections *a* and *b* are together and form the sides and ends of the mold for the slug, and the mold-cavity formed by these sections is open at opposite ends through its entire length.

The mold B is adapted to be rocked by the movement of the shaft D, so as to bear against the alined matrices A, as shown in Figs. 2 and 3. In this position one face *c* bears against said matrices, and the opposite face *d*, which is parallel to the face *c*, forms a flat seat, against which the nozzle C is adapted to bear. Thus in operating, while the parts are in this position the molten metal is ejected from the nozzle beside the entire series of matrices, and the separate jets of metal formed by the apertures *e* in the nozzle are all directed in parallel lines against the corresponding matrices. The result is that the metal is uniformly chilled by the mold, and all parts of the casting are equally perfect.

As preferably constructed, the section *a* of the mold is bifurcated at *f* to embrace the lug *g* of the section *b*, through which the shaft D passes. The furcations *f* are apertured to receive the shaft D. The section *b* has a portion *h*, which forms the upper side of the mold in position for casting. Secured to each end of this portion are the cheek-plates *i*, which are secured to the body portion *j* of the section. These cheek-plates, together with the portion *j*, form a socket for receiving the section *a* and holding it in exact position relative to the section *b*. Portion *a* is of such

a length that a space *k* is left between the top of portion *a* and the bottom of portion *h* when the portions *a* and *b* are in alignment. A feather *m* is made on the top of portion *a*, so as to form a recess in the slug. The body portion *j* is out of alignment with portion *h*, and the cheek-plates *i* extend inwardly and then upwardly from this body portion. Thus a shoulder *b'* is formed for the nozzle *C*, and the body *j* is below the space *k* and to one side thereof. Space *k* forms the mold-cavity.

In operation the matrices are first aligned. The mold *B* is then swung upward by the rocking of the shaft *D* until the face *c* thereof contacts with the matrices. During the movement of the mold the nozzle *C* is also moved until it bears against the face *d*. The molten metal will then be ejected to fill the mold, after which the nozzle is first withdrawn and then the mold is swung downward. When the section *a* reaches about the horizontal position, it is unclamped from the shaft through the disengagement of the spring *E* by mechanism not shown. The section *a* will thus remain stationary during the further travel of the section *b*, thus opening the mold and permitting the slug which is held by the feather *m* to be removed by an endwise movement. In the succeeding operation the section *b* is first turned upward to close with the section *a*, after which both sections travel together until they are in contact with the matrices.

What I claim as my invention is—

1. The combination with a series of aligned matrices, of a reciprocating nozzle for the molten metal and an oscillating intermediate mold formed in two sections, with a transverse space between said sections forming the mold said sections being movable in relation to each other.

2. The combination with a series of aligned matrices, of a reciprocating nozzle, and an intermediate mold formed in two sections, one

section fitting in the other section, the inner section being shorter than the outer section so as to form a space between the ends of the sections said sections being movable in relation to each other and means for temporarily locking the sections together.

3. The combination with a series of aligned matrices, a reciprocating nozzle for the metal, and an oscillating intermediate mold formed in sections said sections being movable in relation to each other.

4. The combination with a series of aligned matrices, a reciprocating nozzle for the metal and an oscillating intermediate mold formed in sections said sections having a transverse slot between their ends and being movable in relation to each other.

5. The combination with a series of aligned matrices, a reciprocating nozzle, and an intermediate mold, said mold consisting of two sections one section being provided with side plates supporting a top piece *h* and the other section fitting in said section so as to leave a space between its end and the top piece *h* of the other section said sections being movable in relation to each other and means for temporarily locking the sections together.

6. The combination with a series of aligned matrices, of a reciprocating nozzle for the molten metal, an oscillating shaft, an intermediate mold formed in sections carried by said shaft, one of said sections being rigidly secured to the shaft and the other section being loosely connected thereto so that one section has movement in relation to the other, and means for locking the sections together.

In witness whereof I have hereunto set my hand in presence of two witnesses,

JAMES BENJAMIN ALLEN.
